UNITED STATES PATENT OFFICE.

MANALCUS G. KEERAN, OF BLOOMINGTON, ILLINOIS.

CAR-SEAT.

SPECIFICATION forming part of Letters Patent No. 425,328, dated April 8, 1890.

Application filed October 24, 1889. Serial No. 328,020. (No model.)

To all whom it may concern:

Be it known that I, MANALCUS G. KEERAN, a citizen of the United States, residing at Bloomington, in the county of McLean and State of Illinois, have invented certain new and useful Improvements in Car-Seats; and I do hereby declare the following to be a full, clear, and exact description of the invention, such as will enable others skilled in the art to 5 which it appertains to make and use the same.

My invention relates to an improvement in car-seats, the object of the same being to provide a back-rest for the seat, which may be readily reversed and inclined at various angles.

A further object is to provide devices of the above character which shall be simple and economical in construction and durable and efficient in use; and with these ends in 20 view my invention consists in the certain features of construction and combinations of parts, as will be hereinafter fully described, and pointed out in the claim.

The invention is illustrated by a view, partly 25 in section and partly in side elevation.

A represents the side bars of the car-seat, to which are secured pivotally the lever-arms B. To the outer ends of said arms are pivoted the connecting-rods D. The operating- 30 arms E are pivoted to the connecting-rods at their upper ends, the lower ends thereof being slotted and provided with the ratchets F, the same being adapted to engage the pin G, by means of which the desired elevation of 35 the arms and back is maintained.

To the bars A are pivoted the angle-levers H, to one end of which are pivoted the operating-rods I, the free ends thereof being slightly curved and engaging the lower part of the operating-arms E.

From the above description it will be seen that by pulling forward the operating-rod I the angle-lever H will elevate the operating-arms E, thereby detaching the ratchets F from the pins G and enabling an adjustment 45 of the back at any angle, and, if desired, the back can be carried over, thereby reversing the same.

The angle-levers and operating-bars are placed on each side and in opposite directions to each other, one being adapted to incline the back in one direction and the other to have the reverse effect.

Having fully described my invention, what I claim as new, and desire to secure by Letters 55 Patent, is—

In a car-seat, the combination, with pivoted lever-arms B, connecting-rods D, and operating-arms E, having ratchets in their lower ends, of an angle-lever engaging said operating-arms, and operating-rods to elevate said operating-arms E, substantially as shown and described.

In testimony whereof I affix my signature in presence of two witnesses.

MANALCUS G. KEERAN.

Witnesses:

JOHN B. FRY,
SAIN WELTY.
